UNITED STATES PATENT OFFICE.

BERT A. BROWN, OF BRISTOL, CONNECTICUT.

PNEUMATIC DEVICE APPLICABLE TO RIVET-HEATING FURNACES.

SPECIFICATION forming part of Letters Patent No. 661,950, dated November 20, 1900.

Application filed May 12, 1900. Serial No. 16,450. (No model.)

To all whom it may concern:

Be it known that I, BERT A. BROWN, a citizen of the United States of America, having my residence and post-office address at Bristol, in the county of Hartford and State of Connecticut, have invented a certain new and useful Improvement in Pneumatic Devices Applicable to Rivet-Heating Furnaces, of which the following is a description, reference 10 being had to the accompanying drawings, wherein—

Figure 1 is a view, largely in central vertical section, of a rivet-heating furnace embodying said improvement. Fig. 2 is a view 15 in central longitudinal section, on a larger scale than in Fig. 1, of the valve apparatus in Fig. 1. Fig. 3 is a detail sectional view of a portion of the valve and valve-cylinder on the plane denoted by the dotted line xx . Fig. 4 is a view of the face of the valve-bonnet. 20

The object of the improvement is the production of an apparatus in the nature of a pneumatic device applicable to a rivet-heating furnace.

25 In the accompanying drawings the letter a denotes a rotatable valve of a conical shape exteriorly. It is borne in a valve-cylinder b , which is interiorly shaped to conform to the conical shape of the valve.

30 The letter c denotes the valve-bonnet screwing upon the valve-cylinder.

The letter a' denotes the valve-stem, which has upon it an operating wheel, handle, or lever.

35 The letter d denotes a spring interposed between the valve and valve-bonnet, whose tendency it is to hold the valve snugly to its seat. In order that it may not perform this function unduly, there is a nut e carried on the 40 valve-stem and bringing up against a proper surface on the valve-bonnet. The nuts e and e' embrace between them the spring f . On the outer face of the valve-bonnet there are stop-mortises c' for this spring to drop into, 45 these stop-mortises being coincident in position with the valve-conduits in the valve soon to be described.

The valve-cylinder is pierced by a fluid-pressure inlet g , which is connected by a suitable pipe with a source of fluid-pressure, in 50 the present case and for the purposes of a rivet-heating furnace an air-reservoir con-

taining air at, say, seventy-five pounds pressure.

The letter h denotes valve-conduits in the 55 valve. By the rotation of the valve they are capable of being brought severally and successively into connection, one at a time, with the fluid-pressure inlet g of the valve-conduits h and of the interior diameter of the jet-tubes i that they are all of ample size to allow 60 that in changing from one jet-tube to the next in series with the pressure "on" there is never a time when the stream of air is cut off completely.

The letter i denotes jet-tubes severally appurtenant to the several valve-conduits. Each has a delivery-orifice at the end. It is an important and essential feature of the fluid-pressure inlet g of the valve-conduits h and of the interior diameter of the jet-tubes i that they are all of ample size to allow 65 the initial pressure of the compressed fluid to extend to the point of delivery from the jet-tubes. These jet-tubes, which may be more or less in number, have delivery-orifices 70 of different sizes, so that by bringing one or another of them into connection with the source of fluid-pressure more or less of the fluid under pressure may have delivery 75 through the valve, as desired.

The letter k denotes a stop carried on the outer face of the valve, and l denotes a co-operating stop carried on the inner face of the valve-bonnet.

The letter m denotes a conducting-tube removed from said jet-tubes, but in line with the stream of fluid delivered by a jet-tube when it is in connection with the source of fluid-pressure, wherefore the center of the conducting-tube m is not in line with the center of the valve. 80

The letter n denotes a conduit adapted to admit fluid, or, at least, flowing material, to contact and mixture with the stream of fluid flowing from a jet-tube. The upper part of 85 the construction connecting the tube m with the valve parts is preferably a closed dome, as shown. Cases may arise when it may be preferable to have that connection spider-like or open-work. As shown in Fig. 1, the 90 conducting-tube m delivers below the twyer of a furnace, which is well adapted for the purpose of heating rivets near by the place where they are to be used and set. In that 100

furnace, *o* denotes the furnace-casing, the interior of which practically forms an expansion-chamber *p*.

The letter *r* denotes the fire-pot; *s*, the twyer; *t*, the bail; *u*, the floor or bottom supported on perforated flange to admit air, and *v* a door or hand-hole to permit cleaning of the chamber *o*.

The pressure of the fluid flowing through the apparatus is reduced in the operation, the device being in that regard a transference from higher to lower pressure; but in the case of that fluid being air, with air admitted freely at conduit *n*, there is a great increase in volume—an addition of one to eight times the volume which escapes from a jet-tube. The delivery of the air below the fire-pot in the furnace tends to cool the fire-pot, and, conversely, the fire-pot tends to heat the air before it passes through the twyer.

I claim as my improvement—

1. In combination; the valve-cylinder containing the fluid-pressure inlet; the rotatable valve provided with plural valve-conduits and

connecting jet-tubes adapted to be brought 25 successively into connection with the source of fluid-pressure; and the conduit adapted to admit fluid or flowing material to contact and mixture with fluid flowing from a jet-tube; all substantially as described and for the purposes set forth. 30

2. In combination; the valve-cylinder containing the fluid-pressure inlet; the rotatable valve provided with plural valve-conduits and connecting jet-tubes adapted to be brought 35 successively into connection with said fluid-pressure inlet; the conducting-tube centrally in line with the center of a jet-tube when in connection with the source of fluid-pressure and opening beneath the twyer of the furnace; and the conduit adapted to admit air to contact and mixture with the fluid flowing from the jet-tube; all substantially as described and for the purposes set forth. 40

BERT A. BROWN.
